K. FRENZEL

AUTOMATIC NUMBERING DEVICE FOR PRINTING PRESSES

Filed June 22, 1925

Inventor:
Kurt Frenzel

UNITED STATES PATENT OFFICE.

KURT FRENZEL, OF LEIPZIG-STOTTERITZ, GERMANY.

AUTOMATIC NUMBERING DEVICE FOR PRINTING PRESSES.

Application filed June 22, 1925, Serial No. 38,796, and in Germany December 22, 1924.

- In order to number continuously printed matter directly in a printing press numbering devices have been designed adapted to be inserted directly into the composition. 5 A device of that kind is composed of a plurality of number-disks supported upon a shaft located in a box, the disks being turned in a certain appropriate succession, and always by one digit. According as said disks 10 are operated, two systems of those devices are distinguished. With one of them the box enclosing the shaft carrying the number-disks is supported elastically in another box in such a manner that the roller formed 15 by the disks projects over the composition. When then, while the printing proceeds, the printing cylinder or the platen contacts with said roller the inner box in which the said roller is arranged is depressed within 20 the outer box, and is raised later on automatically, when the cylinder or the platen no longer presses upon the number roller, while at the same time pawls provided in 25 said outer box cause a partial rotation of one or several number-disks according to the number to be printed, the partial rotation of one disk amounting always to one digit.
- In order to prevent the print from being 30 obliterated by the rotating number-disk, a mechanism is provided by which every step-motion of the disks is so delayed that it takes place only after the paper has come out of contact with the roller formed by 35 said disks. This mechanism, however, is complicated and sensitive and does not always operate satisfactorily. Besides the 40 numbering devices provided with a mechanism of the kind just stated and having two boxes, of which one is located within the other, require comparatively much space so that the number printed is positioned somewhat remotely from the other printing.
- The second of the two systems referred to 45 in the first paragraph of this introductory part of this specification is not possessed of the drawback mentioned in the second half of the preceding paragraph. There is only one box and the shaft carrying the number 50 disks is supported rotatably therein, but cannot be moved in any other manner. The step-wise movement is effected by causing the printing cylinder or the platen to depress either a separate number-mark or a 55 separate star-shaped mark which projects above the respective number and is elastically 60 movable, the step-wise movement taking place when the printing cylinder or the platen commences to move back into its initial position. As the number-mark or the star-mark is located in another height than the appertaining number-disk it is difficult to ink both at a time as the respective-mark, owing to its projecting over the respective disk, penetrates deeper into the inking roller 65 than do the digits whereby the surface is pressed down too much, in consequence whereof the proper contact of the inking roller with the digit located nearest the respective mark is at least partly prevented. 70 It is possible, it is true, to increase the distance between the mark and the digit in a certain measure but that entails the possibility that the printed digit may be unintentionally altered afterwards by the subsequent imprint of the next digit. Besides, 75 the surface is easily damaged by the projecting mark effecting the next step-motion so that the inking roller bearing that surface must be exchanged repeatedly. If, 80 as is often times desirable, the number-mark or the star-mark is not to be printed, the inking roller, especially if the printing press is a high-speed press, must be provided with recesses at the places concerned in order to 85 prevent inking of that mark. But those recesses render the inking roller unsuited for other printing purposes, and besides, that contrivance can be made use of only if, besides the digits or numbers, no other 90 matter is to be printed.
- The disadvantages and drawbacks stated in the preceding paragraph are obviated by my improved automatic numbering device, the gist of which resides in the features that 95 the shaft carrying the digit disks is supported elastically in the box, that is to say, in one box, and that the step-wise movement of the disks is effected by depressing that shaft, as is more fully described here- 100 inafter.

My invention is illustrated diagrammatically and by way of example in the accompanying drawing in which Figure 1 is a side-view of the shaft and the disks, the box 105 or, more precisely, frame being shown in vertical section; Figure 2 is a rear-view of the parts shown in Fig. 1; Figure 3 is a vertical section in the plane 3-3 of Fig. 1; Figure 4 is a vertical section in the plane 110 4-4 if Fig. 1; and Figure 5 is a plan.

On the drawing *a* denotes a U-shaped

frame, the upright vertical parts of which are each provided with a vertical slot and the bottom-part of which is provided with a recess. The ends of a shaft *b* are supported in said slots, and number-disks *c*, as well as a separate mark-disk *d*, are carried loosely upon said shaft. The ends of the shaft are preferably flattened in such a manner that the shaft cannot turn in the 10 said slots. One end of the shaft is provided with a practically horizontal slot which is engaged by a horizontal pin *e* supported in the vertical frame member in which that end of the wall is located. The 15 other end of the shaft is supported by a compressive spring *f* pressing that end of the shaft against a ledge *g* affixed to the top surface of the respective frame member and closing the respective vertical slot. Normally, the shaft *b* is in an oblique position 20 as shown in Figs. 1 and 2. Through the higher end of it extends a horizontal pin *h* which projects at both ends, these latter engaging two grooves *i* which are provided 25 in the walls of the slot and are not exactly vertical, the arrangement being such that the shaft is shifted axially a little (to the left in Fig. 1, and to the right in Fig. 2) when it is depressed at its higher end.

30 Each number-disk is provided laterally with a ratchet-wheel *k* co-operating with a feed-pawl *l* and a check-pawl *m* subjected to the pressure of a spring *n*. The check-pawls *m* are carried loosely on a shaft 35 *o* supported in a U-shaped member or frame *P* carried by the shaft *b*. The feed-pawls are connected with each other and form in their entirety a kind of comb having prongs of different length. Also this comb is supported in a U-shaped member or frame *Q* also carried loosely by the shaft *b*, and is 40 pressed against the ratchet wheels *k* by a spring *r*. That part of the member or frame *Q* which is located on the higher part of the shaft *b* is provided with a recess *s* which 45 is engaged by a pin *t* projecting forth from the adjacent side-wall of the main frame of the device. When the shaft is depressed, the member or frame *Q* is turned relatively 50 to the shaft by reason of the pin *t* being guided in the recess *s*, and the pawls which are in engagement with the ratchet-wheels are withdrawn so that they are in the position to operate when next being actuated.

55 Generally, only the unit-pawl is in engagement with its appertaining ratchet-wheel, whereas the other ones which are stepped in length are located in a certain distance from the appertaining wheels. When the unit 60 disk shows the digit 9 and is turned by one digit so that 10 must appear, the unit feed-pawl enters into a particularly deep recess of the unit disk ratchet-wheel, and this being so the shorter tens feed pawl enters also 65 into the correspondingly located recess of

the ratchet wheel of the tens disk which is, therefore, also turned by one digit, viz from 0 to 1, whereas the unit disk is being turned from 9 to 0, the result being 10.

The same arrangement is provided for the 70 hundreds-disk and the thousands-disk, whereas the ten-thousands-disk must be turned by hand, as with similar numbering devices. I am aware of the fact that this way of turning numbering disks in steps is 75 known.

The degree of obliquity of the shaft and, thus, its vertical movability at its elevated end can be regulated by means of a screw *u* provided in the ledge *g*. This adjustment 80 is effected in this way that the vertical movability of the shaft is shorter when the working speed of the printing press is increased, the object of this manner of adjusting being to prevent the numbering 85 disks from being flung round.

The other ledge (*v*) located over the lower end of the oblique shaft may be provided with a star-mark which is printed adjacent the end of the number and the object of 90 which is to prevent the final number from being tampered with.

The disk *d* located on the high end of the shaft *b* and bearing the sign "No." can be turned upon the shaft, so that said sign 95 can be turned away to one or the other side, there being then printed merely the number, without the prefix "No."

The frame *a* is closed laterally by plates 100 *z*, so that the types between and among which the numbering device is inserted are held securely at all sides of this device.

An important feature of the invention is that the step-wise rotation of the number-disks is effected by moving the roller formed 105 by the number disks down and up in the box formed by the frame and the lateral plates *z*. The oblique position of the shaft carrying the number disks is provided solely for the purpose of causing the several disks, i. e. the consecutive unit-disk, tens disk, hundred disk, thousand disk, and so on, to contact with the sheet of paper to be printed upon in the proper order and with the displacement of the set of disks in actual directions 110 such as occurs during the oscillating movement of the disks avoids shifting of the imprint with respect to the printing surface.

I claim:

1. An automatic numbering device for 120 printing presses, comprising, in combination, a casing; a shaft extending longitudinally through said casing in oblique position and being so supported therein as to be adapted to be depressed; a set of number-disks carried by said shaft; and means for turning said disks in a certain order when the said shaft is being elevated, as set forth.

2. An automatic numbering device for 130 printing presses, comprising, in combination,

a casing; a shaft extending longitudinally through said casing in an oblique position and being so supported therein as to be adapted to be depressed at its higher end, 5 and having a horizontal transverse groove in its lower end; a stationary pin supported in said casing and engaging said groove; a set of number-disks carried by said shaft; and means for turning said disks in a certain 10 order when the said shaft is being elevated, as set forth.

3. An automatic numbering device for printing presses, comprising, in combination; a casing; a shaft extending longitudinally through said casing and being so supported therein as to be adapted to be depressed and to be moved also axially by being depressed; a set of number disks carried by said shaft; and means for turning said 20 disks in a certain order when the said shaft is being elevated, as set forth.

4. An automatic numbering device for printing presses, comprising, in combination, a casing having a vertical slot in each 25 end; a horizontal pin crossing one of said slots; an oblique shaft having at one end a horizontal transverse groove engaged by said pin; another pin arranged in horizontal position crosswise in the other end of the said shaft and engaging with its projecting ends vertical grooves provided in the side-walls of the slot in the respective end of the casing and being slightly curved in such a way that the shaft is shifted axially when being depressed at the respective end which is the 35 higher one; a set of number-disks carried by said shaft; and means for turning said disks in a certain order when the said shaft is being elevated, as set forth.

5. An automatic numbering device for printing presses comprising, in combination, a casing; a shaft extending longitudinally through said casing in oblique position and being so supported therein as to be adapted to be depressed; a set of number-disks carried by said shaft; a corresponding set of ratchet wheels, each pertaining to, and being connected with, one of said number-disks; a corresponding set of feed-pawls, and a bow carrying them and being so supported as to be adapted to be turned; a corresponding set of check-pawls, and a stationary bow supporting them, substantially as set forth. 40 45 50

6. An automatic numbering device for printing presses, comprising, in combination; a casing; a shaft extending longitudinally through said casing in oblique position and being so supported therein as to be adapted to be depressed; a set of number-disks carried by said shaft; a corresponding set of ratchet-wheels, each pertaining to, and being connected with, one of said number-disks; a corresponding set of feed-pawls, and a bow carrying them and being so supported as to be adapted to be turned; a corresponding set of check-pawls, and a stationary bow supporting them; a pin affixed to the casing at the end where the higher end of the said shaft is located, and engaging a slot provided in the adjacent portion of the bow carrying the feed-pawls, and being adapted to turn this bow when the shaft is being depressed whereby said latter pawls are brought into operative position so as to turn the number wheels when said latter bow 60 65 70 75 re-assumes its former position.

In testimony whereof I affix my signature.
KURT FRENZEL.
